ELWYN Z. COLE, OF PHILADELPHIA, PENNSYLVANIA.

LOCK NUT.

Application filed January 23, 1924. Serial No. 688,033. Renewed September 22, 1927.

My invention relates to new and useful improvements in lock nuts, and has for its object to provide an exceedingly simple and effective device of this description which 5 will provide for the setting of the nut at any position on its bolt and locking it against retrograde movement.

A further object of my invention is to provide for the ready unlocking of the nut so 10 that it may be backed off without injury to any of the parts.

With these and other ends in view, this invention consists in the details of construction and combination of elements hereinafter 15 set forth and then specifically designated by the claims.

In order that those skilled in the art to which this invention appertains, may understand how to make and use the same, I will 20 describe its construction in detail, referring by numerals to the accompanying drawings forming a part of this application, in which:—

Fig. 1, is a side elevation of a nut in position upon a bolt showing one form of my 25 invention.

Fig. 2, is a side elevation of a portion of the nut.

Fig. 3, is an end view of the bolt showing 30 the spline grooves therein.

Fig. 4, is a face plan view of the locking washer.

Fig. 5, is an edge view of Fig. 4.

Fig. 6, is a face view of the nut.

Fig. 7, is an inner plan view of the retaining cap.

Fig. 8, is an edge view of Fig. 7.

Fig. 9, is an elevation of a slightly modified form of my invention the retaining cap being broken away to show the operating parts in position.

Fig. 10, is a perspective of the retaining cap.

Fig. 11, is a view similar to Figs. 1 and 45 9, showing a further modification of my invention.

Fig. 12, is a plan view of the split ring washer utilized in the construction shown in Fig. 10.

Fig. 13, is an edge view of Fig. 11.

Fig. 14, is a face view of the nut shown in Fig. 11.

Fig. 15, is a plan view of the locking

washer used in the construction shown in Fig. 11.

Fig. 16, is a section at the line 16—16 of Fig. 15.

Fig. 17, is a bottom plan view of the retaining cap used in Fig. 11.

Fig. 18, is an edge view of Fig. 17.

Fig. 19, is a plan view of a still further modification of my invention.

Fig. 20, is a side elevation of Fig. 19, a portion of the retaining cap or housing being broken away to show the arrangement of 65 the parts of the device in position.

Fig. 21, is a perspective of the retaining cap or housing used in the construction shown in Figs. 19 and 20.

In carrying out my invention as embodied 70 in Figs. 1 to 8 inclusive, 1 represents a nut having a hub 2 formed therewith and this hub has the teeth or serrations 3 formed upon the face thereof said teeth being preferably in the form of ratchet teeth.

4 represents a locking washer which has formed upon its inner face a series of teeth or serrations 5 adapted to engage with the teeth 3 upon the hub and this locking washer is provided with the spline lugs 6 adapted 80 to run in the spline grooves 7 formed lengthwise of the bolt 8 upon which the nut 1 is threaded.

9 represents the retaining cap which in this particular form of my invention consists of a disc having the strips 10 formed therewith and bent at right angles thereto, each of said strips carrying a lug 11 at the lower end thereof which may consist of a pin secured therein in any suitable manner. 90 These pins are adapted to pass into the bayonet slots 12 which are formed diametrically opposite each other in the hub 2.

13 represents a spring preferably a conical spiral spring and this spring is interposed 95 between the top of the retaining cap and the outer face of the locking washer so that when the lugs 11 are locked into the bayonet slot this spring will serve the double purpose of holding the teeth 5 into engagement with the teeth 4 and also preventing the accidental displacement of the lugs 11 from the slots 12 as will be readily understood.

From this description the operation of my improvement will be obviously as follows:—

The nut having been run upon the bolt

sufficiently to permit the end of the bolt to project beyond the hub 2 the locking washer 4 is placed in position by the spline lugs 6 being run in the spline grooves 7 after which 5 the spring 13 is placed upon the locking washer and the retaining cap is forced downward against the spring so as to partially compress the same when the lugs 11 are in the offset portions of the bayonet slots 12. 10 When the parts are thus assembled the nut may be run downward upon the bolt until its inner face has jammed against the work intended to be held during which operation the teeth 3 will slide under the teeth 5 after 15 the manner of a ratchet but when the nut has been screwed home it cannot be backed off since the teeth 5 engaging with the teeth 3 will prevent any retrograde movement of the nut and since the locking washer 4 is 20 prevented from revolving independent of the bolt as before described the nut cannot be accidentally displaced.

When it is desired to remove the nut it is only necessary to force the retaining cap 25 slightly downward and turn it upon its axis until the lugs 11 come into alignment with the vertical portion of the bayonet grooves 12 when this cap may be removed giving free access for the removal of the spring 13 and 30 the locking washer 4 after which the nut may be readily backed off.

In Figs. 9 and 10, I have shown a slightly modified form of my invention as above described and in which the retaining cap 9^a is in the form of a housing which completely encloses the spring locking washer and the greater portion of the hub 2 so that when the device is assembled and in use the parts are protected.

40 In Figs. 11 to 18 inclusive, I have shown a still further modification of my invention in which the hub 2 has an annular groove 14 formed around its circumference the retaining cap 9^b having its arms 10^b so formed as to provide shoes 15 adapted to fit into said groove said arms being sufficiently resilient to permit the shoes to be sprung over the upper edge of the hub into the groove.

In this form of my invention instead of 50 using a locking washer having ratchet teeth formed thereon I prefer that the locking washer 4^a be of a metal softer than the metal of which the nut is made so that by forming serrations or file teeth 16 upon the 55 face of the hub 2 this washer when brought in firm contact with said serrations will permit the embedding of said serrations in its surface so as to prevent any retrograde movement of the nut. Also in this form 60 of my invention I prefer to use a split ring spring 17 which when forced against the locking washer by the cap 9^b will occupy comparatively small space so as to make the assembled device exceedingly compact.

65 Another advantage of this construction

is that the file like serrations 16 when embedded in the locking washer will hold the nut against rotation in either direction which in certain classes of work is very desirable since the nut may be locked without being jammed against a surface.

When it is desired to unlock a nut embodying this form of my invention a suitable tool such as a screw driver is inserted beneath the shoes or the arms carrying said shoes and said shoes are pried outward so as to clear the groove 14 and permit the cap to be drawn from off the bolt and the split ring spring and locking washer also removed.

80 In the modification of my invention shown in Figs. 19 to 21 inclusive, I provide a housing cap 9^c the body of which is adapted to fit over the nut 1 while a turret 20 formed with said cap is adapted to enclose or house the projecting end of the bolt 8. A spring arm 21 is formed from the body of the cap by the slots 22 and the lower end of this spring arm is turned inward to produce the locking lug 23 the latter being adapted to engage with the notch 24 formed in the inner face of the nut.

85 When this form of the invention is used any desired form of spring and locking washer may be utilized, but in Fig. 20 I have utilized the soft metal washer 4^c and the split ring 17.

90 When it is desired to remove this form of cap a pointed tool is inserted through the hole 25 and the arm 21 sprung outward to a degree that will free the lug 23 from the notch 24 and thus permit the ready withdrawal of the cap for unlocking the nut.

95 Heretofore great difficulty has been experienced in locking a nut upon a bolt so as to prevent any retrograde movement of said nut and at the same time permit the ready removal of the nut when occasion required, but I have entirely overcome this disadvantage by the several simple constructions here shown all of which embody the principle of utilizing a locking washer and held by the bolt against independent rotation and a retaining cap held to the nut in such manner 105 as to permit the effective action of a spring in holding the locking washer in engagement with teeth or serrations upon the nut.

110 Of course I do not wish to be limited to the exact details of construction as herein shown as these may be varied within the limits of the appended claims without departing from the spirit of my invention.

115 Having thus fully described my invention, what I claim as new and useful is:

120 1. A lock nut comprising a nut having serrations, a bolt on which said nut is threaded, said bolt having spline grooves therein, a locking washer having serrations for engagement with the serrations on the 125 130

nut, lugs carried by the washer adapted to run in the spline grooves, a cap adapted to be locked to the nut or unlocked therefrom, and a spring interposed between the cap and locking washer.

2. In a device of the character described, a bolt having lengthwise spline grooves therein, a nut adapted to thread upon said bolt, a hub formed with the nut, ratchet teeth formed upon the face of said hub, a locking washer splined upon the bolt, ratchet teeth formed upon one face of said washer, said teeth adapted to engage the teeth upon

the hub, a cap surrounding the hub and enclosing the washer, lugs carried by said cap for engagement with bayonet slots formed in the hub whereby said cap may be locked to and unlocked from the hub, and a spring interposed between the top of the cap and the washer for forcing the teeth of the latter into engagement with the teeth carried by the hub.

In testimony whereof, I have hereunto affixed my signature.

ELWYN Z. COLE.
